UNITED STATES PATENT OFFICE.

CLAES RYDEN, OF CRANSTON, RHODE ISLAND, ASSIGNOR TO UNIVERSAL WINDING COMPANY, OF PORTLAND, MAINE, A CORPORATION OF MAINE.

WINDING-MACHINE.

1,141,583.

Specification of Letters Patent.

Patented June 1, 1915.

Application filed April 18, 1913. Serial No. 761,983.

To all whom it may concern:

Be it known that I, CLAES RYDEN, a citizen of the United States, residing at Cranston, in the county of Providence and 5 State of Rhode Island, have invented certain new and useful Improvements in Winding-Machines, of which the following is a specification.

My invention relates to improvements in 10 winding machines and particularly to the traverse-mechanism therefor.

The object of my improvement is to provide a traverse-mechanism capable of minute adjustment for different lengths of 15 traverse or throw of the winding-guide and particularly designed to insure a more constant speed of traverse of the guide throughout the full extent of its movement to insure an accurate and precise disposition of the 20 separate convolutions or windings of material. The device is particularly intended for machines used for winding wire in manufacturing coils for electrical purposes where a regular and uniform relation of 25 the windings is most essential.

The invention is fully described in the following specification, illustrated by the accompanying drawings, in which like letters of reference designate like parts.

30 In the drawings:—Figure 1 is a front elevation of a winding machine showing my new traverse-mechanism applied thereto; Fig. 2 is a detail view of the rocker-arm of the traverse-mechanism; Fig. 3 is a side view of the same; Fig. 4 is a view of the 35 traverse-arm connected with the traverse-guide; Fig. 5 is a side view of the same; Fig. 6 is a sectional view of the link-connecting means of the traverse-mechanism taken 40 on the line *a—a* of Fig. 4, looking in the direction indicated by the arrow *q*; Fig. 7 is a diagrammatic view of the principal elements of the traverse-mechanism illustrating its improved method of operation.

45 Referring first to Fig. 1, *B* designates the frame of a usual type of winding machine having bearings for the horizontal winding-spindle *b* and cam-shaft *c*. Mounted on the shaft *c* is a traverse-cam *C* which is rotated 50 through driving connections illustrated at *D*, and including a driving-pulley *d*, but not here shown in detail. Secured to the front side of the frame *B* is a bracket *E*, formed with an arm *e* reaching in toward the cam 55 *C*. At the end of the arm *e* is a bearing

e' for the stud or rocker-shaft *f* which carries the traverse rocker-arm *G*.

Referring to Figs. 2 and 3, the arm *G* is provided with a hub *g* made integral with or secured to the shaft *f* and formed with a depending arm *g'* having a boss or hub *g''* at its lower end. Projecting from the hub *g''* is a pin *h* on which is rotatably mounted a roll *j* adapted to engage the groove *c'* of the traverse-cam *C*. The cam *C* rocks the arm *G* through the roll *j* and the motion derived therefrom is transmitted to the traverse-guide from an upwardly extending arm or lever *K*. This latter is preferably formed as a separate piece constructed of sheet-metal and attached to the arm *G*. Any convenient means for attaching the two arms *G* and *K* together might be used, and as here shown the arm *K* is mounted on a projecting portion of the shaft *f* with its lower end *k* fitted to inclose a turned down portion *g'''* of the hub *g''*. Suitable pins or screws *l* secure the arm *K* against the hub *g* so that the parts *G* and *K* move together as one element.

Referring again to Fig. 1, the bracket *E* is formed with an upwardly extending arm *e''* having a hub *e'''* at its upper extremity. Extending from the hub *e'''* is a rod *M* arranged parallel with the winding-spindle *b*. The outer end of the rod *M* is supported in a bearing *n* which surmounts a vertical arm *N* secured to a horizontal rod *O*. The rod *O* projects from a boss *e''* on the side of the bracket *E* and is held in place by a screw *e''*. Mounted to slide on the rod *M* is a sleeve *p* which carries a pivoted arm *R* to which is attached the winding-guide *r* adapted to bear on the winding-spindle *b* and to swing upward therefrom as the winding is built up on the spindle. Surrounding the sleeve *p* and secured thereto by the set-screw *s* is a sleeve or bushing *S*. Fastened to the sleeve *S* by the screws *t* is a depending plate or arm *T* which I term the traverse-guide arm. The lower edge of the arm *T* is fitted to slide in a longitudinal slot *o* formed in the rod *O*, see Figs. 4 and 5.

The rocker-arm *K* is formed with a longitudinal slot *k'* and the traverse-guide arm *T* is provided with a similar slot *t'*. Extending between the two arms *K* and *T* is a link *U* arranged with its terminal connecting-means adjustable in the slots *k'* and *t'*.

Referring to Figs. 4, 5 and 6, the right-

hand end of the link U carries a pin u extending through a stud V which is adapted to slide in the slot t' of the arm T. The stud V is formed with a head v bearing against the inner face of the arm T and its outer end is threaded to receive a nut v' . Interposed between the nut v' and the arm T is a washer W formed with a spline or key w which is fitted to the slot t' to keep the washer from turning. Projecting from the periphery of the washer W is a finger or pointer w' having a beveled straight-edge w^2 adapted to register with the graduations t^2 of a scale running alongside the slot t' . The 15 end of the pin u is scored with a peripheral groove u' into which is sprung a split-ring u^2 that abuts the end of the stud V and holds the pin in place. By tightening the nut v' against the washer W the latter binds the 20 head v against the arm T to hold the stud V in position in the slot t' . By loosening the nut the stud can be adjusted up and down in the slot.

The connection of the opposite end of the 25 link U with the arm K is made with practically the same arrangement. Projecting from the end of the link is a pin x which extends through a stud y fitted to the slot k' . Sprung into a groove x' at the end of the 30 pin x is a split-ring x^2 which holds the pin in place in the stud. Extending upwardly from the rear end of the stud y is an arm Y at the end of which is a second stud y' also projecting through the slot k' and carrying a nut y^2 . On the stud y' is a washer Z similar in form to the washer W and having a key z and index pointer z' . The pointer z' can be adjusted along the 35 graduations k^2 when the nut y^2 is released, and the stud y is normally held in its adjusted position by tightening the nut against the washer Z. The purpose of the extension or arm Y is to raise the washer Z above the 40 pin x to prevent it from interfering with the hub g of the rocker-arm G when the end of the link U is adjusted to a point adjacent the axis of the arm. That is to say, this arrangement allows the pin x to be slid down on the arm K to a point close to the axis of the 45 arm without causing the washer Z to strike the hub g. To increase this clearance the hub g may be cut away at g^4 , as illustrated in Figs. 2 and 3. The graduations on the arms K and T are so related that when 50 the pointer z' is set at a certain mark on its scale and the pointer w' adjusted to register with the corresponding mark on the arm T both ends of the link U will be at the same height above the axis of the arm K. In 55 other words, the link U will be in a horizontal position, or level. It is this feature of maintaining the link U level or substantially parallel with the line of movement of the winding-guide which provides for a 60 more uniform speed of traverse of the 65

guide irrespective of its extent of traverse, as hereinafter more fully explained.

The operation of my improved device is as follows: Referring to Fig. 1, after it has been determined what extent of traverse of the winding-guide r is to be used to wind the package of yarn or coil of wire to the dimensions required, the pointer z' is adjusted to the proper mark on the scale of the arm K, the graduations being preferably designated by characters or figures, not here shown. The pointer w' is then adjusted to the corresponding graduation on the scale of the arm T to insure a level position of the link U. The nuts y^2 and v' are then tightened to hold the link U in place on the arms K and T while allowing its ends to swivel on the pins u and x. The machine is now ready to operate and when power is applied through the driving-pulley d the winding-spindle b and cam C are rotated with the proper ratio of speed, as provided for by a system of gears or other intermediary mechanism, not herein shown or described. The cam C acts through the roll j to impart an oscillatory motion to the arm K which is transmitted through the link U to cause reciprocation of the arm T which slides in the slot o of the rod O. The arm T being connected to the sleeve p causes the latter to slide back and forth on the rod M and as the sleeve p carries the arm R and winding-guide r the latter will be reciprocated to traverse along the winding-spindle b. The movement of the 95 rocker-arm K as imparted by the cam C is constant, but its range of action can be regulated, as before described, through adjustment of the point of connection of the link U toward or away from the axis of the 100 arm. The amplitude of oscillation of the point of connection of the link on the arm controls the extent of traverse of the guide r and thus the length of the layers of windings can be regulated within certain limits. 110

I am aware that it has heretofore been proposed in winding mechanisms to regulate the extent of traverse of the winding-guide by adjusting its point of connection on the oscillating arm from which its reciprocatory motion is derived. My present improvement consists particularly in providing means to effect this adjustment without causing an inconstant speed of reciprocation of the guide when its extent of traverse is shortened as now explained. 115

To illustrate graphically the advantages of my present arrangement over similar devices already in use, reference is made to Fig. 7 of the drawings which is a diagrammatic representation of the usual mechanism for reciprocating the winding-guide from an oscillating arm to allow for adjustment of the length of traverse of the guide. The axis on which the oscillating rocker-arm 125

pivots is designated by 2, and the extremes of movement of its upper end are shown at 3 and 4, while 5 represents its mid-position. The full lines 6, 7 and 8 represent the link or connection between the arm and the guide and the two extremes of traverse of the guide are shown at 9 and 10 and the mid-position at 11. It will be seen that the extreme upward point of connection 5 of the link on the arm, when the latter is in mid-position, lies in the same horizontal plane with the point of connection 9, 10 or 11 of the link with the guide, this being the usual arrangement. Now, when the connecting link is adjusted as above described to transmit the maximum extent of throw of the arm to the guide the speed of traverse of the latter will remain substantially constant from 9 to 10 and back again. This is demonstrated by the fact that the point 11 is substantially equidistant from the points 9 and 10. There will, of course, be a slight variation in the speed of the guide as the point of connection 3 travels upward on the arc 12 to the point 5 and down again to 4, but this is not of material moment. That is to say, the slight increase in speed of the guide as the point 4 moves to 5 and the slight retardation therein from 5 to 6, due to the change in angularity of the link 7 on account of the arcuate path of travel of the point 4, is practically imperceptible. When, however, the point 4 is adjusted toward the axis 2 of the rocker-arm to shorten the throw of the guide this change in the angularity of the link with respect to the horizontal line 7 becomes more marked and consequently there is a considerable variation in the speed of traverse of the winding-guide. This change is illustrated graphically by the dash lines 14, 15, 16 which represent the positions of the link at the two extremes of oscillation of the rocker-arm and also at the mid-position of the latter. The positions of the thread-guide at these intervals are designated respectively 17, 18, 19. The opposite connecting-point of the link on the rocker-arm at one extreme of traverse is represented at 20; at 21 at the other extreme; and at 22 when the rocker-arm is in mid-position. Assuming that the point of connection of the link with the guide remains in the horizontal plane of the line 7, which is the usual arrangement as before explained, and that the opposite point of connection 3 is moved down on the rocker-arm to 20 to effect a shorter traverse of the guide, then the following variation in speed of the guide must take place: As the point 20 moves to 22 the speed of the guide will be accelerated, while as the point 22 moves to 21 the speed of the guide will be decreased. This is shown graphically by the disparity in distance between the points 17 and 19 as compared to the distance between the

points 19 and 18. In other words, the winding-guide will move a greater distance during the first half of the oscillation of the rocker-arm, as the point of connection of the link moves from 20 to 22, than during the last half, when the point 22 moves to 21, as shown by the lines 23 and 24. This change in speed of the guide from one end of the traverse to the other affects the laying of the windings as follows: It will be understood that the ratio of speed between the winding-spindle and guide remains constant after once being adjusted to give the proper disposition of the convolutions or turns of the windings in relation to each other. For instance, in winding wire into electrical coils the speed ratio of the spindle and guide are so adjusted that the turns or helices of the wire will be laid contiguous or one close to another throughout all of the layers of the coil. Now, if this ratio is fixed so that the helices of wire are laid in close juxtaposition to each other during the first part of the traverse of the guide, or from 17 to 19 in Fig. 7, then, with the arrangement of traverse-mechanism above described, when the guide continues its traverse from 19 to 18 the turns of the wire will be crowded together so that they cannot be deposited in a smooth layer. Putting it another way, since there are the same number of turns or convolutions of the wire from 17 to 19 as from 19 to 18 the turns in the first portion of a layer must be farther apart or wound more "open" than the turns in the last part.

To return to the practical phase of the subject, it has been demonstrated that with the usual arrangement of mechanism adapted to wind with the traverse of the guide adjustable in length to suit different commercial requirements, the laying of the turns or convolutions in the winding cannot be accurately controlled to give them a uniform disposition, that is an exact spacing, throughout each layer. This is a most important consideration and my present improvement is especially designed to meet the requirements of accurate, uniform winding. With the novel arrangement herein disclosed it is proposed to adjust the point of connection of the link U with the guide exactly in proportion to the adjustment of the point of connection of the link on the rocker-arm. In brief, the connecting-link between the rocker-arm and the guide is so arranged as to provide for maintaining it always in a horizontal position whatever the relation of its point of connection to the axis of the rocker-arm may be, and hence the speed of traverse of the guide is not open to the influence of changes in angularity of the link.

My new device is extremely simple in structure and mode of operation, but notwithstanding this, it has manifest advantages as above pointed out. As before

stated, it is particularly adapted to machines employed for winding wire or other conducting material into electrical coils, and it is most important in such work that the 5 windings be regular and uniform throughout the whole coil. Heretofore it has been extremely difficult to obtain this uniformity, particularly with very fine wire, and my improvement is therefore of utmost importance 10 as applied to this field. It will be understood, however, that my new traverse-mechanism is equally well adapted for other purposes and to other types of winding machines than that here shown.

15 Various modifications might be made in the form and arrangement of my new device without departing from the spirit or scope of the invention;

20 Therefore, without limiting myself to the exact construction shown and described, what I claim is:—

25 1. In a winding machine, the combination with the winding-spindle and traverse-guide, of an oscillating rocker-arm for reciprocating the guide, a corresponding arm attached to the guide, a link connecting the two arms, means to adjust said link on both arms with respect to the axis of oscillation of the rocker-arm, and index devices on 30 both arms for indicating the extent of adjustment at each end of the link to provide for an accurate setting thereof at both of its ends to insure a constant speed of traverse of the guide and a uniform spacing of 35 the coils of winding.

40 2. In a winding machine, the combination with the winding-spindle and traverse-guide, of means to support the guide to adapt it to be reciprocated in a path parallel with the axis of the spindle, a rocker-arm, means to oscillate the rocker-arm, a link connecting the rocker-arm with the guide, means to adjust the link bodily to vary its position in relation to the axis of 45 oscillation of the rocker-arm while maintaining it substantially parallel with the path of travel of the guide, and index devices for indicating the extent of adjustment at each end of the link to provide for 50 an accurate setting thereof at both of its ends to insure a constant speed of traverse of the guide.

55 3. In a winding machine, the combination with the winding-spindle and traverse-guide, of an oscillating arm for reciprocating the guide, said arm formed with a longitudinal slot, a similar arm attached to the guide and also formed with a corresponding slot, a link connecting said arms, means 60 at the ends of the link slideable in the slots to adjust the link on both arms to vary the length of traverse of the guide, and index devices on both arms for indicating the extent of adjustment at each end of the link 65 to provide for an accurate setting of the lat-

ter at both of its ends to insure a constant speed of traverse of the guide.

4. In a winding machine, the combination with the winding-spindle, of a rod arranged parallel with the spindle, a sleeve slideable on said rod, a traverse-guide mounted on the sleeve, an arm attached to the sleeve, an oscillating rocker-arm, a link connecting the two arms and adjustable on both of them to vary the extent of traverse of the 75 guide without causing an inconstant speed of traverse thereof, and index devices on both arms for indicating the extent of adjustment at both ends of the link to provide for an accurate setting thereof.

5. In a winding machine, the combination with the winding-spindle, of two rods arranged parallel with said spindle, a sleeve slideable on one of the rods, a traverse-guide mounted on the sleeve, an arm attached to the sleeve and arranged to slide on the opposite rod, an oscillating rocker-arm, a link connecting the two arms and adjustable on both of them to maintain it substantially parallel with the rods during the oscillation 90 of the rocker-arm, and two separate index devices to indicate the extent of adjustment at each end of the link to provide for an accurate setting of the latter at both of its ends to insure a constant speed of traverse 95 of the guide.

6. In a winding machine, the combination with the winding-spindle and traverse-guide, of an arm connected with said guide and provided with a longitudinal scale having graduations, an oscillating rocker-arm having corresponding graduations, a link connecting said arms and adjustable on both of them, and index pointers at the ends of the link adapted to register with the graduations on the arms to indicate the extent of adjustment at each end of the link to insure a proper setting of the latter at both of its ends to provide for a constant speed of traverse of the guide.

7. In a winding machine, the combination with the winding-spindle and traverse-guide, of an arm connected with said guide and formed with a longitudinal slot having graduations along its edge, an oscillating rocker-arm also formed with a slot having corresponding graduations, a link connecting the arms, studs at the ends of the link adapted to slide in the slots of the arms, and index pointers on the studs adapted to register with the graduations on the arms to indicate the extent of adjustment at each end of the link to insure a proper setting of the latter at both of its ends to provide for a constant speed of traverse of the 125 guide.

8. In a winding-machine, the combination with the frame, of a winding-spindle and cam-shaft mounted in bearings on the frame, a cam on the cam-shaft, a bracket attached 130

to the frame and formed with a bearing, a rock-shaft mounted in said bearing, a rocker-arm on said shaft adapted to be oscillated from the cam, two rods extending from the bracket parallel with the winding-spindle, a traverse-guide slidable on one of the rods, an arm connected with said guide with its opposite end adapted to slide in a slot in the other rod, a link connecting the two arms and adapted to be adjusted longitudinally thereof, and index devices on

both arms to indicate the extent of adjustment at each end of the link to insure an accurate setting of the latter at both of its ends to provide for a constant traverse of 15 the guide.

In testimony whereof I affix my signature in presence of two witnesses.

CLAES RYDEN.
